BY ATTORNEY

UNITED STATES PATENT OFFICE.

CHARLES H. SEELY, OF NOROTON, CONNECTICUT.

GOLF-CLUB.

1,026,181.

Specification of Letters Patent. Patented May 14, 1912.

Application filed January 19, 1912. Serial No. 672,203.

To all whom it may concern:

Be it known that I, CHARLES H. SEELY, a citizen of the United States, residing at Noroton, Fairfield county, Connecticut, have 5 invented certain new and useful Improvements in Golf-Clubs; and I do declare the following to be a full, clear, and exact description of the invention, such as will enable others skilled in the art to which it app- 10 pertains to make and use the same.

My invention relates to golf clubs and has for its objects, to improve the balance of the club, to throw a relatively larger portion of the weight of the head nearer 15 the medial line of the striking face thereof, to lighten the shank of the head, and to so secure the shaft to such shank as to insure a resiliency at a location near the head itself, and with these ends in view my in- 20 vention consists in certain details of construction and combination of parts herein-after fully described and then particularly pointed out in the claims which conclude this description.

25 In the accompanying drawing Figure 1 is a perspective view illustrating a golf club constructed in accordance with my improvement the shaft being broken away—Fig. 2 a detail perspective of the head of such 30 club—Fig. 3 a vertical longitudinal section of the club head, and Fig. 4 a detail broken view of the lower portion of the shaft.

Similar numerals of reference denote like parts in the several figures of the drawing.

35 Heretofore, golf clubs of all descriptions have sometimes been made with hoses of more or less lengths, a wooden club having a short hose to afford a socket for the insertion of the bottom of the shaft, while 40 the hose of an iron club was considerably longer and likewise afforded a socket for the insertion of the lower end of the shaft.

The length and weight of the shafts of 45 golf clubs, and also the weight of the heads of such clubs, do not vary materially because they are standardized, so to speak, but very little, if any, attention has been paid to the relative distribution of weight between the hoses and the heads of the clubs. Also, due attention being given to 50 the general strength of the club, nothing has been accomplished in the way of constructing the hoses in such manner that they shall possess a certain degree of resiliency, whereby the head will yield slightly to the impact against a ball and instantly

recover so as to add considerably to the driving distance of such club.

My invention aims toward the perfection of golf clubs in the above named particu- 60 lars and will be best understood from the following description.

1 represents the blade of an ordinary iron club and 2 the striking face thereof. The hose of the club is divided so as to form two spaced vertically disposed resilient tangs, 3, 4, which preferably diverge from the bottom upward and may be tapered according to the amount and location of resiliency desired. 65

The spacing between the tangs 3, 4, is preferably continued downwardly through the heel of the club as seen at 5, in Fig. 3, and the shaft 6 of the club has its lower portion 7 slightly tapered as usual so as 70 to fit snugly between the tangs 3, 4, the extreme lower end of the shaft having an enlargement 9 which fits within the opening 5 in the blade of the club, said shaft being secured in position by means of rivets 8 75 driven through the tangs and the portion 7.

If desired, in order to afford a more finished appearance, the usual winding may be effected around the tangs 3, 4, and the lower end of the shaft. 80

Of course the opening 5 need not extend clear through to the bottom edge of the blade, and also such opening may extend as far forward of the blade as may be deemed desirable. 85

The mere addition of wooden faces to the front and rear faces of the blade 2 would transform an iron club into what is known in golf circles as a "Driver" or a "Brassie". 90

By forming the hose as is shown in the drawing, the shank portion of the club is made considerably lighter than the ordinary hose of an iron club, and this will increase the proportion of the weight of the blade as compared with the weight of the hose, 100 which is greatly to be desired. Furthermore, the club will possess a resiliency at the tang portion, and this resiliency may be localized along said tangs according to the nature of the taper of the latter; for 105 instance, a taper such as is shown in the drawing will throw the resiliency higher up on the tang than would a taper of such tangs in a reverse direction, that is to say, a taper caused by making the tangs wider 110 at the tops and narrower at the bottoms.

I do not wish to be limited to any par-

ticular manner of forming this taper, since the gist of my invention resides in the broad idea of providing a golf club with upwardly extending spaced resilient metal tangs, between which the lower end of the shaft may be secured.

Having thus described my invention what I claim as new and desire to secure by Letters Patent is:—

- 10 1. A golf club, comprising a blade or head, spaced resilient metal tangs extending vertically from the heel of said blade or head, and a shaft whose lower extremity is inserted between said tangs and secured thereto.
- 15 2. A golf club, comprising a blade or

head, a pair of spaced resilient diverging and tapered metal tangs extending vertically from the heel of said blade or head, the space between said tangs being continued down through the heel of said club to the bottom edge thereof, a shaft whose lower extremity is inserted within said space so as to be embraced on two opposite sides only by said tangs, and means for securing 25 said shaft and tangs together.

In testimony whereof I affix my signature in presence of two witnesses.

CHARLES H. SEELY.
